AMERICAN PLATEWORK CO., WASHINGTON, D. C.

UNITED STATES PATENT OFFICE.

MICHAEL KIRSHNER, OF LYNCHBURG, VIRGINIA; ABRAHAM S. KIRSHNER ADMINISTRATOR OF SAID MICHAEL KIRSHNER, DECEASED.

MACHINE FOR PACKAGING ARTICLES.

1,058,307.

Specification of Letters Patent.

Patented Apr. 8, 1913.

Application filed February 28, 1908. Serial No. 480,274.

To all whom it may concern:

Be it known that I, MICHAEL KIRSHNER, a citizen of the United States, and a resident of Lynchburg, in the county of Campbell and State of Virginia, have invented certain new and useful Improvements in Machines for Packaging Articles, of which the following is a specification.

This invention relates to improvements in machines for putting up packages of articles, such for example as cigarettes and the object of my invention is to construct a machine which will make it possible for blanks to be fed onto a table and through suitable sets of mechanisms which are timed to perform their services at the proper moment during the path of the movement of the blank, the package is completely formed without any further handling by an attendant.

In the preferable embodiment of my invention the blank is scored then automatically fed onto a support where the articles to be packed are fed onto one portion of the blank while another portion of the blank, such as the flap for example, is pasted. Then the blank is folded so as to incase the articles being packed after which the flap is secured in position by means of the previously applied paste. The partially formed package is now fed forward and after being ejected is folded upon itself and then suitably delivered through a discharge chute.

The preferable, though not necessary, embodiment of my invention is shown in the drawings accompanying and forming part hereof in which—

Figure 1 and Fig. 1^a show my complete machine in side elevation. Fig. 2 and Fig. 2^a show the machine in top plan with the table partly stripped and the cigarette hopper and feeding mechanism removed. Fig. 2^b is a section through the line 2^b—2^b of Fig. 2^a. Fig. 3 and Fig. 8 represent a sectional view through the line 3—3^a of Fig. 1 and Fig. 1^a. Fig. 4 represents a sectional view on an enlarged scale of the cigarette feeding mechanism and also the scoring and pasting mechanisms. Fig. 5 is a horizontal section of the cigarette feeding mechanism through the line 5—5 of Fig. 1. Fig. 6 is a vertical section of the machine through the line 6—6 of Fig. 1. Fig. 7 is a section through the line 7—7 of Fig. 1^a. Fig. 8 is a sectional

detail of the scoring mechanism through the line 8—8 of Fig. 5. Fig. 9 is a sectional detail on an enlarged scale through the line 9—9 of Fig. 1. Fig. 10 is a vertical section through the line 10—10 of Fig. 1. Fig. 11 is a sectional detail of the main shaft and its various cams. Figs. 12, 13 and 14 are details of the flap folding devices. Fig. 15 is a perspective detail of one of the folders. Figs. 16 and 17 are views of the pasting mechanism. Fig. 18 is a view of the cam and connected parts for operating the scorer and the plunger. Fig. 19 is a view of the cam and connected parts for feeding the cigarettes. Fig. 20 is a view and connected parts for folding the flaps. Fig. 21 is a view of the cam and connected parts for operating the cigarette support. Fig. 22 is a view of the cam and connected parts for operating the ejector. Fig. 23 is a view of the cam and connected parts for operating the pusher to shove the pack of cigarettes off of the ejector. Fig. 24 is a perspective view of the cam and part of the lever shown in Fig. 23. Fig. 25 is a perspective view of the through forming part of the cigarette feeding means. Fig. 26 is a perspective view of one of the movable trays. Figs. 27 and 28 (shown on the same sheet as Fig. 4 in order to show the position they occupy on the table) are respectively a plan view of the blank and a plan view of the package partly made up. Fig. 29 is a view partly in section showing the cigarettes just after they are fed on the blank and the edge of the flap being pasted. Fig. 30 is a similar view after the cigarettes have been moved downward under the table into a tray. Fig. 31 is a similar view after the plunger has been moved upward and during the operation of the folders. Fig. 32 is a view just as the tray is feeding the boxes of cigarettes under the table, in the act of folding the flap down upon the package; the right hand end of this figure showing another tray with its completely pasted package in position. Fig. 33 is a perspective view of the package as it appears in the right hand end of Fig. 32. Fig. 34 is a perspective view of the package as its two members are being folded upon each other in the folding chute just before it is delivered to the package delivering chute.

Before referring to the details of the drawings by numerals it may be well to state that in this machine a blank is used, pref-

erably of the shape shown in Fig. 27 and this blank goes through the successive stages shown in Figs. 27 to 34 inclusive, the object being to form a completely wrapped package of cigarettes which will be doubled upon itself as shown in Fig. 34 and which may be opened to the shape shown in Fig. 33 so that the cigarettes or other articles may be easily withdrawn from the package 10 as the articles are used.

Referring now to the drawings by numerals: 1 designates the main frame which is of the shape shown more particularly in Fig. 1 and Fig. 1^a. This main frame supports a main or driving shaft 3 which as shown in Fig. 11 is connected by gears 4 and 5 to a counter-shaft 6 to which power is given by means of fast and loose pulleys 7 and 8. The main frame 1 also supports two shafts 10 and 11 and these shafts are for the purpose of supporting drums which in turn support endless carriers to move a series of trays.

The drums are designated 13 and 14, the drums 13 being shown in Fig. 1 and the drums 14 being shown in Fig. 1^a. In Fig. 10 is shown a section through the line 10—10 of Fig. 1 where the construction of the drums 13 may be better seen. As there shown it will be seen that they support two endless bands 16 and 17 to which are secured at regular intervals a succession of trays 19, these trays being shown in perspective view in Fig. 26 where it will be seen that each tray extends clear across from one drum to the other and is secured to the endless bands 16 and 17. Each tray has two openings 20 in its bottom, for a purpose to be hereinafter described and two upwardly projecting arms 22 which, as the endless carrier is moved, travel through a slot or opening 24 in the table 26 supported on top of the main frame 1. The construction is such that when the shaft 10 is rotated as will be described, the endless carrier is also given movement to cause the trays to pass from and around one drum 13 across the machine to the other drum 14 and in passing at the top from the drums 13 to 14 the trays travel within the slot or opening 24 formed in the table 26, and during this movement the arms of the trays 19 project upwardly through the aforesaid slot 24 and are of sufficient height to extend just above the top of the table as indicated in Fig. 1. This makes it possible for an attendant to place a blank as X of the shape shown in Fig. 27 in the position shown at the extreme left hand end of Fig. 1 and in such a manner that the arms 22 will engage or straddle the middle portion α of the blank and thus, as the carrier moves, cause the arms 22 to move said blank across the top of the table as the tray moves from the left hand drums 13 to the right hand drums 14. In order

to give the drums 13 and 14 the necessary movement, I secure to the shaft 10, on which the drums 13 are secured, a ratchet wheel 28 which is provided with two pawls 29 and 30, the first pawl, 29, being employed to give motion to the ratchet wheel 13 and the other pawl, 30, to prevent said ratchet wheel from rotating backward. The first pawl 29 moves with a crank arm 31 which is pivotally connected by a rod 32 with a lever 33 pivoted to the main frame at 34. This lever has a cam roller 35 which co-acts with a cam A shown in Figs. 1 and 11 which I shall designate the carrier cam. This carrier cam A, as it rotates with the main shaft 3, co-acts with the parts just described and through the medium of the cam roller, lever 33, rod 32, crank arm 31 and pawl 29, at a certain period of movement of the shaft 3 imparts to the said pawl 29 a rotary movement which moves the ratchet wheel 28, a movement sufficient to carry the trays a distance equal to the distance from the center of one tray to the center of the next tray. The said carrier cam A is of such shape that after this movement takes place the carrier and its trays 22 will be held stationary until the enlarged part of the cam again moves around so as to repeat the operation just referred to. It follows from this that the trays 19 carried by the endless bands 16 and 17 are given a step by step movement so that if we take, for example, the tray shown in Fig. 1 as being just below the extreme left hand end of the table 26, the next revolution 100 of the carrier cam A will cause this tray to move to the position where it projects upward through the table and is located immediately over the shaft 10 in said Fig. 1. There the tray remains until the cam makes another 105 revolution when the tray is moved to the next or second position. Then the tray stays there until another revolution of the cam when the tray is moved to the third position; and so on until the tray leaves the 110 table, passes around the drums 14 shown in Fig. 1^a and then travels under the table back to the left hand drums 13.

As soon as the carrier moves to the position where it is immediately over the shaft 10, shown in Fig. 1, an attendant places a blank like that shown in Fig. 27 so that the arms 22 straddle the central portion α of the blank and then the blank is in such a position as to be ready to be moved by the tray arms 22 until it is scored, packed with cigarettes, pasted, folded, and finally ejected. The first of these operations is the scoring and this is done at the third position in Fig. 1 where it will be seen that there is a scoring mechanism comprising (see Figs. 8 and 18) scoring blades 87 projecting downwardly from a head 88 and movable so that the scoring blades 87 will be forced downward upon the blank which at this time is supported

upon a bed 39 of rubber or other suitable material, this bed as well as the table 20 having a slot through which passes the tray arms 22 before referred to. The scoring blades 37 are for the purpose of scoring or creasing the blank as shown by lines in Fig. 27. It will be seen that the scoring blades score in parallel lines, the inner set marking the same shape as the bottom of the package or the bottom of the tray; and the outer set defining the height of the package, so that the blank will more readily fold upon right angles thus providing a square cornered box instead of having rounded edges.

In order to give downward movement to the scoring blades 37 I connect their head 38 by means of rods 40 with a lever 41 which is connected by a rod 42 with a cam lever 43 pivoted to the main frame at 44 and having at its free end a cam roller 45 which co-acts with a cam B shown in Figs. 11 and 18 which I shall designate a scoring and plunger cam. The construction is such that when the main shaft 3 rotates, the scoring and plunger cam B moves the roller 45 to force downward the lever 43 and through the parts 40, 41 and 42 cause the head 38 and scoring blades 37 to take a downward movement, forcing the blades 37 in contact with the blank which at this time is stationary and supported on the rubber bed 39. It will be understood that this movement is of course timed to take place at the moment when the drums 18 and 14 and the endless carrier trays are stationary. After the head 38 and its scoring blades 37 have been given the downward movement just described to score the blank, and then have been given their upward movement to return them to the position shown in Fig. 1, the next rotation of the main shaft 3 through the carrier cam A moves the blank forward one step so that the next blank is scored and the forward movement of the blank which has just been scored moves it under the cigarette hopper and feeding mechanism, or rather the tray and its arms 22 move the blank from the first position shown in Fig. 4 to the second position shown in Fig. 4 where the blank has been caused to pass under a guide 47 which is slotted at 48 for the passage of the carrier arms 22. The parts rest in this position until the blank at the rear has been scored and then the blank moves forward to the third position which is at the other side of the cigarette hopper as shown in Fig. 1. When it reaches the position at the right hand of the cigarette hopper shown in Fig. 1 the blank is in the proper position to receive a double charge of cigarettes and also to have its flap pasted, and the mechanism for performing these functions will now be described.

The cigarette hopper 50 is shown more particularly in Figs. 1, 4, 5 and 9 and as

there shown the hopper has a division wall 51 so arranged that the cigarette will be separated into two lots, one lot being over a charging wheel or drum 53 and the other set being over a similar charging wheel or drum 54. These drums are secured to and rotate with a shaft 55 and they are arranged with blades 56 projecting from the periphery thereof as shown best in Fig. 4, these blades being so arranged that as the charging wheels or drums rotate under the cigarettes the cigarettes will fall into the passages formed by the blades 56 and be carried around under the wheels or drums and fed onto the blank in a manner to be described. In order to give the charging wheels or drums an intermittent rotary movement, or a step by step movement, their shaft 55 has secured to it a ratchet wheel 57 (see Figs. 5 and 19), and with this ratchet wheel co-acts a pawl 58 supported by a crank arm 59 projecting from a sleeve 60 from which also projects a second crank arm 61 which is connected with a rod 62 with a cam lever 63 pivoted at 64 and having a cam roller 65 which co-acts with a cam C which I shall designate the cigarette cam C. At each rotation of the main shaft 3 the cigarette cam C through the cam roller 65 and the parts 57, 58, 59, 60, 61, 62 and 63 operates the shaft 55 to give the charging wheels or drums 53 and 54 a partial rotation, thus feeding the cigarettes as shown in Fig. 4. In order to properly feed the cigarettes or other articles, the bottom of the hopper is formed with the delivery chute or trough shown in Fig. 25. This chute or trough is formed with a curved member 63 which forms a casing around the bottom of the charging wheels or drums 53 and 54 and the chute or trough is provided with two outside flanges 64 and 65 and with a separating wall 66 which projects between the two charging wheels or drums 53 and 54 and is of just the right width to hold the cigarettes separated a distance equal to the width of the central portion σ of the blank shown in Fig. 27. The bottom of the chute or trough is provided with a central passage 67 shown in Fig. 25 through which may pass the arms 22 of the trays 19 as said tray and arms move a blank underneath the chute or trough 63. The bottom of the trough or chute 63 continues under the bottom of the charging wheels or drums and retains the cigarettes in two separated charges so that when delivered they are surrounded by a rectangular frame 68 forming the end of the aforesaid chute or trough 63 (see Fig. 25). This rectangular frame 68 is a fixture and is located at the position shown in Figs. 1 and 4 and when a tray reaches the point when it is immediately under this rectangular frame 68, the tray stops and at this point the blank

X is so located that its body portions X¹ and X² are immediately under the rectangular frame 68 and its flaps are to the right thereof as shown in Figs. 1 and 20 when they are in the position to be pasted. As soon as the blank reaches this point the cigarette cam C which is timed to feed the cigarettes just at this moment is rotated to force a charge of cigarettes out of the chute or trough 68 so that they are forced into the rectangular frame 68 by which they are confined at the moment that they are resting on the blank X. While the cigarettes are being fed onto the blank the flaps of the blank are being pasted by mechanism as follows:

A sprocket wheel D is keyed to the main shaft 3 as shown in Fig. 11 and a sprocket chain 75 connects this sprocket wheel with a sprocket wheel 76 secured to a shaft 77 shown in Figs. 1, 4 and 16. The shaft 77 as shown in Fig. 16 is the main shaft of the pasting mechanism and this shaft through sprocket wheels 78 and a sprocket chain 80 drives a supplemental shaft 81. The first shaft carries two fountain rollers 82 and 83 revolving in paste reservoirs 84 and 85, and the other shaft 81 drives two rotary brushes 86 and 87 through the medium of gears 88 and 89, each of which has only a single row of bristles which as the brushes 86 and 87 rotate brush against the fountain rollers 82 and 83 and take up a supply of paste therefrom just sufficient to paste the edges of the flaps as said single rows of bristles come in contact therewith, as seen in Figs. 4 and 16. In order to paste the other edges of the flaps, I provide two other brushes 90 and 91 which are arranged at right angles to the other brushes 86 and 87 as shown in Fig. 16, these brushes also having a single row of bristles arranged to contact with fountain rollers 92 and 93 feeding paste from the paste reservoirs 94 and 95. The brushes 90 and 91 are arranged on shafts 96 and 97 on the ends of which are pinions 98 and 99 which mesh with gears 100 and 101 which rotate with the shafts 102 and 103 upon which the aforesaid fountain brushes 90 and 91 are secured and with which they rotate. In order to drive the shafts 102 and 103 and thus rotate the fountain rollers 92 and 93 and the brushes 90 and 91 through the gearing just described, I employ bevel gears 104 and 105 shown in the left hand end of shaft 77 in Fig. 16 and another set of bevel gears 106 and 107 shown near the middle of said shaft in the same figure. As the main shaft 3 is constantly rotating, it follows also that the shaft 77 through the sprocket wheel D, the sprocket wheel 76 and the sprocket chain 75 is also constantly rotating and therefore at every revolution of said main shaft 3 the two sets of pasting brushes 86, 87 and 90, 91 are given a rotation so that the single row of bristles on each of these brushes will take up a sup-

ply of paste from its respective fountain roller and apply the paste to the flap of the blank, and as there are four sets of these bristles arranged as shown in Fig. 16, it follows that the flaps of the blank will be pasted upon their two outer surfaces as shown by the diagonal lines in Fig. 28 and this pasting takes place during the time when the blank X is supported in the position shown at Fig. 29, the pasting being done simultaneously with the moving of the charge of cigarettes onto the blank. The bristles 90 and 91 are slightly in advance of the bristles 86 and 87 so as to avoid interference. Immediately after the simultaneous feeding of the cigarettes onto the blank and the pasting of the edges of the flap, both of which are done when the blank is in the position shown in Fig. 29, the main shaft 3 is at the position when its scoring and plunger cam B causes the downward movement of the scoring blades 87 to score the blank which happens to be under the scoring blades at that time; and simultaneously with this movement, a pair of plungers 110 and 111 which are located over the two charges of cigarettes as seen in Fig. 29, are caused to have a downward movement owing to the fact that the said plungers 110 and 111 are connected to a cross-head 112 to which are connected a pair of rods 113 shown in Figs. 6 and 18. And simultaneously with the downward movement of these two plungers 110 and 111, a double support 114 is likewise caused to descend. This double support comprises two members 115 shown in Fig. 6 as projecting upwardly through the tray 19 and the blank rests upon these supports as shown in Fig. 6. The bottom 114 of these supports is connected by means of rods 116 with a short arm 117 connected to a rock shaft 118 to which is also connected a long arm 119 on the end of which is a cam roller 120 in contact with and operated by the support cam E on the main shaft 3, (see Fig. 21). The construction of this cam E is such that the support 114 is permitted to descend just as soon as the cam E in Fig. 21 moves so that the large part of the cam rotates from under said cam roller 120 and this permits the support to move down so as to enable the blank and the cigarettes to be bodily shoved onto the carrier by the simultaneous downward movement of the plunger 110, these parts then assuming the position shown in Fig. 80. This of course changes the form of the blank, and as the blank has been previously scored it causes the blank to form recesses housing the cigarettes and with the left hand flap projecting upward as shown in said Fig. 80. The parts are kept in the position shown in Fig. 80 sufficiently long to permit the edges of the blank to be folded and I will now describe the mechanism for accomplishing this object.

In Figs. 12, 18 and 14, the folding mechanism is illustrated. In Fig. 12 the blank has just been pasted; cigarettes are in position and the plungers 110 and 111 are on top of the cigarettes, the blank being forced down to the position shown in Fig. 30; therefore the edges of the blank will be projecting upward as shown in said figure. At this time two folders 121 are operated to fold over the projecting edges. These folders 121 are connected to two shafts 122 shown also in Fig. 20. To give movement to the shafts 122 and also to their folders 121 each shaft is provided with a bevel gear 123 which meshes with a segmental rack 124 supported by a short shaft 125 and projecting from the segmental rack is an arm 126 which has a cam roller 127 co-acting with a cam F on the main shaft 3 which I shall designate as the folder cam F. The construction is such and the parts are so timed that when the cam F operates to move the cam roller 127 in one direction the segmental rack 124 is moved in the opposite direction to rotate the bevel gear 123 and the shaft 122 to swing the folder 120 on its shaft. It will be understood that this mechanism is duplicated on the other side of the machine. Now by referring to Figs. 12, 18 and 14 it will be seen that the folders 121 which are shown in their initial positions in Fig. 12 are each provided with a hump 128 and with a projecting end 129. As the folders swing inward through the movement of the folder cam F the humps 128 first contact with the projecting edges of the side flaps shown in Fig. 30 and fold them over to the position shown in Fig. 18, the flaps continuing their swinging movement on their shafts until their projecting ends 129 contact with the other upwardly projecting edges of the blank, as shown in Fig. 18. The continuing movement of the folders causes the projecting ends 128 to fold over the said projecting edge to the position shown in Fig. 14 where it will be seen that the edges of the blank are folded over both on the ends and side. Just before these folders start to perform their work, the plunger cam B has turned around to the point where the plunger is elevated sufficiently to permit the folders to perform their work and after the folders have gotten to the position shown in Fig. 14 the cam roller 120 is permitted by the shape of the support cam E to drop a trifle lower and at this point the main shaft 3 has moved to the position where the carrier cam A is in a position to cause a further movement of the endless carrier and its trays. The parts are now in the position shown in Figs. 4 and 14 and as the carriers move under the influence of the cam carrier A, the folders under the influence of the folding cam which is continuing its movement, also continue their movement a little further so as to hold the

edges in their folded position and the forward movement of the carrier causes the flaps to be moved under the projecting end 133 of the table 26 which acts as a wiper to wipe down the previously pasted flaps onto the previously folded edges of the blank, the beginning of this operation being shown in Fig. 32. As soon as the tray moves completely under the wiping end 133 of the table, the pasted flap is held in sealing position until it reaches the position shown in the right hand end of Fig. 32 where it is held with the parts in sealing contact until another cycle of operations is completed (see also Fig. 2^b). Of course during this movement the plungers 110 and 111 and the double support 114 are all caused to assume an upward movement ready for the next blank to be fed along and acted upon by them.

As the carriers are moved step by step they finally reach the ejecting mechanism which is shown in Fig. 1^a. In this figure 140 represents an ejector which is normally located beneath the table but which is capable of movement upwardly to project up through the carrier so as to shove upwardly the package of cigarettes to the position shown in Fig. 1^a. To cause the ejector to take this movement, I employ a cam G on the main shaft 3 which I have designated an ejector cam G. This cam G operates upon a cam roller 141 supported by a lever 142 pivoted at 143. The other end of this lever connects with a rod 144 which through the movement of the parts just referred to causes the ejector 140 to be given an upward movement through the ejector support 145 and through whichever of the trays 19 happens to be over the ejector support 145 so as to push upwardly the package of cigarettes to the positions shown in Figs. 1^a and 22. After this action takes place, the package of cigarettes which is now of the shape shown in Fig. 33, is bodily pushed off of the ejector 140 and into the folding mechanism. To push the double package of cigarettes off of the ejector 140 I employ a pusher 147 which I shall term the first pusher and this pusher is connected to uprights 148 which project downward and are pivoted at 149 (see Fig. 23) and to which are also pivoted rods 150 (see Figs. 23 and 24) which in turn are connected to levers 151 which are fixed to a rock shaft 152 (see Fig. 24) and to one of which is secured a cam roller 154 co-acting with a cam H which I shall designate as the first pusher cam H. The construction of these parts is such that when the first pusher cam H, which is of course timed to act just after the ejector has moved the package of cigarettes to the position shown in Figs. 1^a and 22, moves its cam roller 154 and through the intermediate parts, the first pusher 147 is caused to push the package of cigarettes off of the ejector 140 as shown in Figs. 1^a, 130

22 and 23 into the package folding mechanism. This folding mechanism is shown in Figs. 1^a and 2^a and preferably consists of two folding blocks 156 and 157 each of which is formed with a recess 158 and 159 which are of the peculiar shape shown in Fig. 2^a. In other words at the entrance of these recesses 158 and 159 their combined width is sufficient to receive the package of 10 cigarettes as it is pushed off of the ejector 140 and then the recesses converge so that as the package of cigarettes is forced into folding blocks 156 and 157 the two parts of the package are gradually doubled upon 15 themselves until they finally fit closer together and are shoved out of the folding blocks 156 and 157 into a delivery chute 160. The first pusher 147 merely pushes the package of cigarettes into the two folding blocks 20 156 and 157 and then the first pusher 147 recedes to the position shown in Figs. 1^a and 2^a and when the next package is shoved off of the ejector, this package shoves the first package farther into the folding blocks until 25 the packages finally are shoved into the said delivery chute 160. In order to make room for the packages in the said chute 160 and to move said packages along so as to make room for the incoming package, I employ a second pusher 162 which is connected to a lever or arm 163 connected to an upright crank arm 164 projecting from a rock shaft 165 shown in Figs. 1^a and 2^a to the other end of which, as seen in Fig. 1, is connected a cam 30 lever 166 having on its end a cam roller 167 co-acting with a cam I which I shall designate as the second pusher cam I, this cam being shown in Figs. 1 and 6. During the operation of this second pusher cam I, the cam lever 166 is shoved outward causing the shaft 165 to move the crank arm 164 and the lever or arm 163 to shove the second pusher 162 into the delivery chute 160, and as seen in Fig. 2^a, this will cause the second pusher 45 to shove the packages of cigarettes which are in the delivery chute 160 forward so as to make room for the next incoming package.

Although I have to some little extent set forth the operation of the various mechanisms of my machine, in describing the details thereof, it may not be amiss to give a separate description of the operation, which is as follows: During the single rotation of the main shaft 3 all the cams A 50 to I inclusive and the sprocket wheel D operate to perform their functions and to operate the various sets of mechanisms, it being understood that they are shaped and timed to cause the various parts to operate 55 at the proper moments. Assuming that a sufficient number of blanks have already been fed onto the table 26 to fill the various trays running through the slot or opening 24 in the table 26, we will follow the course 60 of one of the blanks. As the arms 22 of

one of the trays 19 project upwardly through the slot 24 in the table 26, an attendant places a blank on the table so that the arms 22 engage said blank. As soon as the carrier stops the support cam E 70 through its connections shoves upward the support 114 so that its members 115 project through the open bottom of the tray until the members 115 are flush with the top of the table 26 as seen in Fig. 6 and at this time the support remains stationary so as to support the blank while the double charge of cigarettes is fed onto the blank. Just at this moment the cigarette cam C 75 operates to shove a double charge of cigarettes onto the blank and simultaneously the brushes of the four pasters, through the medium of the sprocket chain 75 and its sprockets, act to paste the edges of the flap of the blank, the blank being now in the position shown in Figs. 1 and 29. During the aforesaid operations of feeding the cigarettes and pasting the flap, the scoring and plunger cam B operates to move down the plungers 110 and 111 to the position shown in Fig. 6 and simultaneously the scoring blades 37 are being moved down by the same cam B. The further rotation of the cams B and E causes the supports 115 and the plungers 110 and 111, with the blank and cigarettes between them, to move bodily downward from the position shown in Fig. 29 to the position shown in Fig. 30 when the blank and the cigarettes are supported in the bottom of the tray which happens to be at that point. During this action the edges of the blank are bent upwardly to the position shown in Fig. 30 and now the scoring and plunger cam B moves so as to permit the plungers to move 90 upward (see Fig. 31) to permit the folders 121 to move inward and fold over the edges of the blank. At this moment the folder cam F has reached the point to rotate the shafts 122 and thus cause the folders to 95 move from the position shown in Fig. 12 to the positions shown in Figs. 13 and 14, the humps 128 of the folders first folding over the end edges and then the projecting ends 129 act to fold over the projecting side edges 100 as shown in Fig. 14. By this time the carrier cam A is again in position to cause a further movement of the endless carriers and their trays and then causes the tray which is immediately under the folders to move 105 forward, and, since the blank and charge have now dropped under the table from the position shown in Figs. 1, 6 and 29 to the position shown in Figs. 4 and 30, the tray passes under the projecting end 133 of the table and said end wipes the previously 110 pasted flap onto the folded down edges of the package as shown in Figs. 32 and 33. While these operations are being performed 115 the package which was previously formed 120 of

and which has reached the position where the ejector 140 is located, is being ejected and packed, the ejector cam G operating through its connections to shove the ejector upward through the tray which happens to be over it, causing the package of cigarettes to be moved out of said tray just in advance of the first pusher as shown in Fig. 1^a. At this time the first pusher cam H acts through its intermediate parts to cause the first pusher 147 to contact with and shove the package of cigarettes off of the ejector 140 and into the two folding blocks 156 and 157. And as each succeeding package forces the one in advance of it until they are finally folded and doubled on themselves in the folding blocks 156 and 157, they are forced into the chute 160, the second pusher 102 being operated by the second pusher cam I so as to make room for each package by shoving the previously delivered package out through the delivery chute 160.

From the foregoing it will be seen that I have invented a machine which automatically moves a blank so as to score it, feed a double charge onto it, paste the edges, fold the blank around the charges, secure the flap to the folded edges of the package by the previously applied paste, eject the package from the forming tray, deliver it into a pair of blocks where it is doubled upon itself, and finally eject it into and through a package delivering chute.

Although I have illustrated and described my machine in considerable detail, it is obvious that my invention is not limited to such details and reference should be made to the appended claims to determine the scope of the invention.

40 What I claim as my invention is:

1. In a packaging machine, a support or table, an endless carrier supporting a series of trays adapted to feed a blank along said support or table while the blank is resting on said support or table, means for charging or filling said blank, and means for moving the charge and the blank into one of the trays, thus folding the blank around said charge while the blank and its charge are moving within the tray.

2. In a packaging machine, a support or table, an endless carrier supporting a series of trays adapted to feed a blank along said support or table while the blank is resting on the said support or table, means for charging or filling said blank, means for moving the charge and the blank into one of the trays, thus folding the blank around said charge while moving within the tray, a pasting device for pasting the edges of the blank, and means for sealing the pasted parts of said blank, thus forming a completed package.

3. In a packaging machine, a support or table, an endless carrier supporting a se-

ries of trays adapted to feed a blank along said support or table while the blank is resting on said support or table, means for charging or filling said blank, means for pasting the edges, and mechanism coacting with said trays for folding the blank around the charge filled therein and forming the package within said trays.

4. In a packaging machine, a support or table having an opening or slot therein, a traveling tray co-acting with said table and having a member projecting through said opening or slot to feed a blank along said table, charging or filling means, and means for folding the blank, within said tray, around said charge.

5. In a packaging machine, a support or table having an opening or slot therein, a traveling tray co-acting with said table and having a member projecting through said opening or slot to feed a blank along said table, means for scoring the blank, charging or filling means, and means for folding the blank, within said tray, around said charge.

6. In a packaging machine, a support or table having an opening or slot therein, a traveling tray co-acting with said table and having a member projecting through said opening or slot to feed a blank along said table, charging or filling means, a support for the blank while receiving the charge, means for moving said blank with its charge into the tray and thereby folding the blank around the charge while moving within the tray, and means for lowering the support as a charge enters the tray.

7. In a packaging machine, a support or table having an opening or slot therein, a traveling tray with an open bottom co-acting with said table and having a member projecting through said opening or slot to feed a blank along said table, charging or filling means, a support movable up through the bottom of the tray to support the blank while receiving the charge, means for moving said blank with its charge into the tray and thereby folding the blank around the charge, and means for lowering the support as a charge enters the tray.

8. In a packaging machine, a support or table having an opening or slot therein, a traveling tray with an open bottom co-acting with said table and having a member projecting through said opening or slot to feed a blank along said table, charging or filling means, a support movable up through the bottom of the tray to support the blank while receiving the charge, a plunger for moving said blank with its charge into the tray and thereby folding the blank around the charge, and means for lowering the support as a charge enters the tray.

9. In a packaging machine, a support or table having an opening or slot therein, a

- traveling tray co-acting with said table and having a member projecting through said opening or slot to feed a blank along said table, means for scoring the blank, charging or filling means, a support for the blank while receiving the charge, and means for moving said blank with its charge into the tray and thereby folding the blank around the charge while moving within the tray.
10. In a packaging machine, a support or table having an opening or slot therein, a traveling tray with an open bottom co-acting with said table and having a member projecting through said opening or slot to feed a blank along said table, means for scoring the blank, charging or filling means, a support movable up through the bottom of the tray to support the blank while receiving the charge, a plunger for moving said blank with its charge into the tray and thereby folding the blank around the charge, means for lowering the support as a charge enters the tray.
11. In a packaging machine, a support or table having an opening or slot therein, a traveling tray with an open bottom co-acting with said table and having a member projecting through said opening or slot to feed a blank along said table, charging or filling means, a support movable up through the bottom of the tray to support the blank while receiving the charge, means for pasting the edges of the blank, a plunger for moving said blank with its charge into the tray and thereby folding the blank around the charge, means for lowering the support as the charge enters the tray, and means for sealing the pasted edges and thereby completing the package.
12. In a packaging machine, a support or table having an opening or slot therein, a traveling tray with an open bottom co-acting with said table and having a member projecting through said opening or slot to feed a blank along said table, means for scoring the blank, charging or filling means, a support movable up through the bottom of the tray to support the blank while receiving the charge, means for pasting the edges of the blank, a plunger for moving said blank with its charge into the tray and thereby folding the blank around the charge, means for lowering the support as the charge enters the tray, and means for sealing the pasted edges and thereby completing the package.
13. In a packaging machine, a support or table, an endless carrier supporting a series of trays adapted to feed the blank along said support or table while the blank is resting on said support or table, means for giving said carrier and its trays an intermittent motion, means for charging or filling said blank, a pasting device for pasting the edges of the blank, means for moving the
- charge and the blank into one of the trays, and means for folding the blank around said charge while within the tray and for sealing the pasted parts.
14. In a packaging machine, a support or table, an endless carrier supporting a series of trays adapted to feed the blank along said support or table, means for giving said carrier and its trays an intermittent motion, a scoring device arranged to score the blank during a period of rest, means for charging or filling said blank, a pasting device for pasting the edges of the blank, means for moving the charge and the blank into one of the trays, and means for folding the blank around said charge while within the tray and for sealing the pasted parts.
15. In a packaging machine, a support or table, an endless carrier supporting a series of trays adapted to feed a blank along said support or table, means for giving said carrier and its trays an intermittent or step by step motion, a scoring device adapted to score the blank during a period of rest, a charging device adapted to charge or fill a blank during a period of rest, a pasting device adapted to paste a blank during a period of rest, means for moving the charge and the blank into one of the trays, and means for folding the blank around said charge while within the tray.
16. In a packaging machine, a support or table, a traveling tray co-acting with said table and adapted to move a blank thereon, means for giving said tray an intermittent motion, means for feeding a charge on said blank during a period of rest, and means for moving the blank and its charge into said tray, thereby folding the blank around said charge while it moves within its tray.
17. In a packaging machine, a support or table, a traveling tray co-acting with said table and adapted to move a blank thereon, means for giving said tray an intermittent motion, means for feeding a charge on said blank during a period of rest, means for moving the blank and its charge into said tray, thereby folding the blank around said charge while it moves within its tray, means for pasting the blank, and means for sealing the pasted parts.
18. In a packaging machine, a support or table, a traveling tray co-acting with said table and adapted to move a blank while it is supported on said table, means for giving said tray an intermittent motion, means for feeding a charge on said blank during a period of rest, means for moving the blank and its charge into said tray, thereby forming the sides, and folding means acting to fold the sides over the charge while within its tray.
19. In a packaging machine, a support or table, a traveling tray co-acting with said table and adapted to move a blank while it

- is supported on said table, means for giving said tray an intermittent motion, means for feeding a charge on said blank during a period of rest, means for moving the blank and its charge into said tray, thereby forming the sides, folding means acting to fold the sides over the charge while within its tray, means for pasting the blank, and means for sealing the pasted parts.
20. In a packaging machine, a support or table, a traveling tray co-acting with said table and adapted to move a blank while it is supported on said table, means for giving said tray an intermittent motion, means for feeding a charge on said blank during a period of rest, means for moving the blank and its charge into said tray, thereby forming the sides, folding means acting to fold the sides over the charge while within its tray, means for pasting the blank, means for sealing the pasted parts, and an ejecting device for ejecting the package from the tray.
21. In a packaging machine, a support or table, a traveling tray co-acting with said table, means for charging or filling a blank, means for inserting the blank with its charge in said tray and thereby partially folding the blank, means for moving the tray with its charge and partially folded blank under the table with its flap wiping the underside of the table, thereby folding the flap over the charge.
22. In a packaging machine, a support or table, a traveling tray co-acting with said table, means for charging or filling a blank, means for inserting the blank with its charge in said tray and thereby partially folding the blank, means for moving the tray with its charge and partially folded blank under the table with its flap wiping the underside of the table, thereby folding the flap over the charge, and means for ejecting the package out of said tray.
23. In a packaging machine, a support or table, a traveling tray co-acting with said table, means for charging or filling a blank, means for inserting the blank with its charge in said tray and thereby partially folding the sides of the blank, means for folding the edges of the sides over the package, and means for moving the tray with its charge and partially folded blank under the table with its flap wiping the underside of the table, thereby folding the flap over the charge.
24. In a packaging machine, a support or table, a traveling tray co-acting with said table, means for charging or filling a blank, means for inserting the blank with its charge in said tray and thereby partially folding the sides of the blank, means for folding the edges of the sides over the package, means for moving the tray with its charge and partially folded blank under the table with its flap wiping the underside of the table, thereby folding the flap over the charge.
25. In a packaging machine, a support or table, an endless carrier supporting a series of trays adapted to feed blanks along said support or table, means for charging or filling the blanks, means for inserting a blank and its charge in one of the receptacles or trays, and thereby partially folding the blank around the charge, and means for moving the tray with its charge and partially folded blank under the table with its flap wiping the underside of the table and thereby folding the flap over the charge.
26. In a packaging machine, a support or table, an endless carrier supporting a series of trays adapted to feed blanks along said support or table, means for charging or filling the blanks, means for inserting a blank and its charge in one of the receptacles or trays, and thereby partially folding the blank around the charge, and means for pasting the blank, and means for moving the tray with its charge and partially folded blank under the table with its flap wiping the underside of the table and thereby folding the flap over the charge.
27. In a packaging machine, a support or table, an endless carrier supporting a series of trays adapted to feed blanks along said support or table, means for charging or filling the blanks, means for inserting a blank and its charge in one of the receptacles or trays, and thereby partially folding the blank around the charge, means for pasting the blank, means for moving the tray with its charge and partially folded blank under the table with its flap wiping the underside of the table and thereby folding the flap over the charge, and means for ejecting the package out of said tray.
28. In a packaging machine, a support or table, a traveling tray moving under said table and having a member projecting up above the table adapted to feed a blank along said table, means for charging or filling the blank, and means for moving the blank and its charge down through the table into the tray.
29. In a packaging machine, a support or table, a traveling tray moving under said table and having a member projecting up above the table adapted to feed a blank along said table, means for charging or filling the blank, means for moving the blank and its charge down through the table into the tray, means for pasting the blank, and means for sealing the pasted parts.
30. In a packaging machine, a support or table, a traveling tray moving under said table and having a member projecting up above the table adapted to feed a blank along said table, means for charging or fill-

- ing the blank, means for moving the blank and its charge down through the table into the tray, means for folding over the sides of the blank, means for pasting the blank, and means for folding over the pasted edge onto the package proper.
31. In a packaging machine, a support or table, a traveling tray moving under said table and having a member projecting up above the table adapted to feed a blank along said table, means for charging or filling the blank, means for moving the blank and its charge down through the table into the tray, and thereby folding the sides of the blank around the charge, a pasting device for pasting the edges of the flap, the flap being folded onto the package proper as the tray moves under the table.
32. In a packaging machine, a support or table, a traveling tray moving under said table and having a member projecting up above the table adapted to feed a blank along said table, means for charging or filling the blank, means for moving the blank and its charge down through the table into the tray, and thereby folding the sides of the blank around the charge, a pasting device for pasting the edges of the flap, the flap being folded onto the package proper as the tray moves under the table, and an ejector for ejecting the completed package from the tray.
33. In a packaging machine, a support or table, an endless carrier supporting a series of trays moving under said table, each tray having a member projecting up above the table adapted to feed a blank along said table, means for charging or filling the blank, and means for moving the blank and its charge down through the table into one of the trays, thereby partially wrapping the blank around the charge.
34. In a packaging machine, a support or table, an endless carrier supporting a series of trays moving under said table, each tray having a member projecting up above the table adapted to feed a blank along said table, means for charging or filling the blank, and means for moving the blank and its charge down through the table into one of the trays, thereby partially wrapping the blank around the charge, means for folding the sides over the charge, and means for pasting the flap, the said flap being folded over and sealed as the tray moves the flap under the table.
35. In a packaging machine, a support or table, an endless carrier supporting a series of trays moving under said table, each tray having a member projecting up above the table adapted to feed a blank along said table, means for charging or filling the blank, and means for moving the blank and its charge down through the table into one of the trays, thereby partially wrapping the blank around the charge.
36. In a packaging machine, a support or table, an endless carrier supporting a series of trays moving under said table, each tray having a member projecting up above the table adapted to feed a blank along said table, means for charging or filling the blank, means for moving the blank and its charge down through the table into one of the trays, thereby partially wrapping the blank around the charge, means for folding the sides over the charge, means for pasting the flap, the said flap being folded over and sealed as the tray moves the flap under the table, an ejector arranged to eject the completed package from the tray.
37. In a packaging machine, a support or table, an endless carrier supporting a series of trays moving under said table, each tray having a member projecting up above the table adapted to feed a blank along said table, means for giving said carrier and its trays an intermittent or step by step motion, means for feeding a charge on said blank during a period of rest, and means for moving the blank and its charge into one of said receptacles or trays, thereby folding a blank around said charge.
38. In a packaging machine, a support or table, an endless carrier supporting a series of trays moving under said table, each tray having a member projecting up above the table adapted to feed a blank along said table, means for giving said carrier and its trays an intermittent or step by step motion, means for feeding a charge on said blank during a period of rest, means for moving the blank and its charge into one of said receptacles or trays, thereby folding a blank around said charge, means for pasting the blank, and means for sealing the pasted parts.
39. In a packaging machine, a support or table, an endless carrier supporting a series of trays moving under said table, each tray having a member projecting up above the table adapted to feed a blank along said table, means for giving said carrier and its trays an intermittent or step by step motion, means for feeding a charge on said blank during a period of rest, means for moving the blank and its charge into one of said receptacles or trays, thereby folding a blank around said charge, means for pasting the blank, means for sealing the pasted parts, and an ejector for ejecting the completed package out of the tray.
40. In a packaging machine, a support or

- table, a pair of drums underneath said table, an endless carrier supported by said drums, means for giving said drums and the carrier a step by step motion, a series of trays supported by said carrier and movable along said table, said trays adapted to carry a blank along the table as the blank rests upon said table, means for feeding a charge on said blank during a period of rest, means for moving the blank and its charge into one of said trays thereby partially wrapping the blank around said charge while it moves within its tray, and means for wrapping the flap of the blank over the charge in said tray.
41. In a packaging machine, a support or table, a pair of drums underneath said table, an endless carrier supported by said drums, means for giving said drums and the carrier a step by step motion, a series of trays supported by said carrier and movable along said table, said trays each having a member projecting through the table to carry the blank along the table, means for feeding a charge on said blank during a period of rest, means for moving the blank and its charge into one of said trays thereby partially wrapping the blank around said charge while within its tray, and means for wrapping the flap of the blank over the charge in said tray.
42. In a packaging machine, a support or table, a pair of drums underneath said table, an endless carrier supported by said drums, means for giving said drums and the carrier a step by step motion, a series of trays supported by said carrier and movable along said table, said trays each having a member projecting through the table to carry the blank along the table, means for feeding a charge on said blank during a period of rest, means for moving the blank and its charge through the table into one of the trays thereby partially wrapping the blank around said charge, and means for wrapping the flap of the blank over the charge in said tray.
43. In a packaging machine, a support or table, a pair of drums underneath said table, an endless carrier supported by said drums, means for giving said drums and the carrier a step by step motion, a series of trays supported by said carrier and movable along said table, said trays each having a member projecting through the table to carry the blank along the table, means for feeding a charge on said blank during a period of rest, means for moving the blank and its charge through the table into one of the trays thereby partially wrapping the blank around said charge, means for folding the edges of the sides over the charge in the trays, and means for wrapping the flap of the blank over the charge in said tray.
44. In a packaging machine, a support or table, a pair of drums underneath said table, an endless carrier supported by said drums,
- means for giving said drums and the carrier a step by step motion, a series of trays supported by said carrier and movable along said table, said trays each having a member projecting through the table to carry the blank along the table, means for feeding a charge on said blank during a period of rest, means for moving the blank and its charge through the table into one of the trays thereby partially wrapping the blank around said charge, means for folding the edges of the sides over the charge in the trays, and means for pasting the flap, and means for wrapping the flap of the blank over the charge in said tray.
45. In a packaging machine, a support or table, a pair of drums underneath said table, an endless carrier supported by said drums, means for giving said drums and the carrier a step by step motion, a series of trays supported by said carrier and movable along said table, said trays each having a member projecting through the table to carry the blank along the table, means for scoring the blank on the line on which it is to be folded, means for feeding a charge on said blank during a period of rest, means for moving the blank and its charge through the table into one of the trays thereby folding the blank on the line previously scored and partially wrapping the blank around said charge, means for folding the edges of the sides over the charge in the trays, and means for pasting the flap, and means for wrapping the flap of the blank over the charge in said tray.
46. In a packaging machine, a support or table, a traveling tray co-acting with said table and having an opening in its bottom, a support arranged to project upwardly through the table and tray when the tray is over said support, means for charging or filling a blank, means for moving the blank and charge downward through the table into the tray, thus partially folding the blank around said charge, and means for lowering the said support as the blank and charge are moved into the tray.
47. In a packaging machine, a support or table, a traveling tray co-acting with said table and having an opening in its bottom, a support arranged to project upwardly through the table and tray when the tray is over said support, means for charging or filling a blank, a plunger for moving the blank and charge downward through the table into the tray, thus partially folding the blank around said charge and means for lowering the said support as the plunger moves the blank and charge into the tray.
48. In a packaging machine, a support or table, a traveling tray co-acting with said table and having an opening in its bottom, a support arranged to project upwardly

through the table and tray when the tray is over said support, means for charging or filling a blank, means for pasting the flap, a plunger for moving the blank and charge downward through the table into the tray, thus partially folding the blank around said charge, and means for lowering the said support as the plunger moves the blank and charge into the tray, and the tray moving the folded blank and charge under the table and thereby folding the pasted flap.

49. In a packaging machine, a support or table adapted to support a blank as it is moved thereupon, a traveling tray co-acting with said table, means for charging or filling a blank while resting on the table, and means for moving the blank and its charge from the table into the tray, thereby partially wrapping the blank around said charge while it moves within its tray.

50. In a packaging machine, a support or table adapted to support a blank as it is moved thereupon, a traveling tray co-acting with said table, means for charging or filling a blank while resting on the table, means for pasting the flap, means for moving the blank and its charge from the table into the tray, thereby partially wrapping the blank around said charge, and means for wrapping the pasted flap over the charge while within the tray and sealing the flap.

51. In a packaging machine, a support or table adapted to support a blank as it is moved thereupon, a traveling tray co-acting with said table, means for charging or filling a blank while resting on the table, means for moving the blank and its charge from the table into the tray, thereby partially wrapping the blank around said charge, and means for folding the sides projecting from the trays over the charge while within the trays.

52. In a packaging machine, a support or table adapted to support a blank as it is moved thereupon, a traveling tray co-acting with said table and having an opening in its bottom, a support movable through the bottom of the tray as the latter moves over the support, means for charging or filling a blank, a plunger for moving the blank and its charge through the table into the tray, means for lowering the said support as the plunger moves the blank and charge downward, and means for folding the flap of the blank over the charge within the tray.

53. In a packaging machine, a support or table, an endless carrier supporting a series of trays adapted to feed a blank along the top of said table, means located above the table for scoring a blank, for charging or filling a blank, and for pasting the flap, and means for moving the blank and charge downward into the tray, thus partially wrapping the blank around the charge.

54. In a packaging machine, a support or

table, an endless carrier supporting a series of trays adapted to feed a blank along the top of said table, means located above the table for scoring a blank, for charging or filling a blank, and for pasting the flap, 70 means for moving the blank and charge downward into the tray, thus partially wrapping the blank around the charge, and means for folding over the edges of the blank projecting above the charge and for 75 securing the pasted flap in position.

55. In a packaging machine, a support or table, an endless carrier supporting a series of trays adapted to feed a blank along 80 the top of said table, means located above the table for scoring a blank, for charging or filling a blank, and for pasting the flap, means for moving the blank and charge downward into the tray, thus partially wrapping the blank around the charge, 85 means for folding over the edges of the blank projecting above the charge and for securing the pasted flap in position, and an ejector for ejecting the package from the trays. 90

56. In a packaging machine, a support or table, an endless carrier supporting a series of trays adapted to feed a blank along the top of said table, means located above the table for scoring a blank, for charging 95 or filling a blank, and for pasting the flap, means for moving the blank and charge downward into the tray, thus partially wrapping the blank around the charge, means for folding over the edges of the 100 blank projecting above the charge and for securing the pasted flap in position, an ejector for ejecting the package from the trays, and a pusher for moving the package off of the ejector. 105

57. In a packaging machine, means for supporting a blank, means for feeding two separate charges on said blank and means for wrapping said blank separately around each of said charges, thus forming a double 110 package.

58. In a packaging machine, means for supporting a blank, means for feeding two separate charges on said blank, means for wrapping said blank separately around each of said charges, thus forming a double package, and means for doubling the package so that one charge is in parallel relation to the other. 115

59. In a packaging machine, a traveling 120 carrier, means for supporting a blank, means for feeding two separate charges on said blank, and means for wrapping the said blank separately around each of said charges while supported by said carrier, thus forming a double package. 125

60. In a packaging machine, a tray, means for feeding two separated charges onto a blank, means for moving said blank and said separated charges into the tray and thereby 130

partially wrapping said blank separately around said separated charges.

5. 61. In a packaging machine, a tray, means for feeding two separated charges onto a blank, means for moving said blank and said separated charges into the tray and thereby partially wrapping said blank around said separated charges, and means for folding a flap over each of said separated charges, thus forming a double package.

adapted to feed a blank along said table, means for charging or filling two separated charges on the blank, and means for moving the blank and its separated charges down through the table into one of the receptacles or trays. 70

68. In a packaging machine, an endless carrier supporting a series of trays adapted 75

10 thus forming a double package.

62. In a packaging machine, a tray, means for feeding two separated charges onto a blank, means for moving said blank and said separated charges into the tray and thereby partially wrapping said blank around said separated charges, means for pasting the edges of the blank, and means for folding flaps over the separated charges and sealing the pasted edges.

15

20 63. In a packaging machine, a tray, means
for feeding two separated charges onto a
blank, means for moving said blank and
said separated charges into the tray and
thereby partially wrapping said blank
25 around said separated charges, means for
pasting the edges of the blank, means for
folding flaps over the separated charges and
sealing the pasted edges, and means for
doubling the package on the line between the
30 two charges so that one charge is in parallel
relation to the other.

64. In a packaging machine, a tray, means for feeding two separated charges onto a blank, means for moving said blank and said separated charges into the tray and thereby partially wrapping said blank around said separated charges, means for pasting the edges of the blank, means for folding flaps over the separated charges and sealing the pasted edges, means for ejecting the double package from said tray, and means for doubling the package on a line between the two charges so that one charge is in parallel relation to the other.

45 65. In a packaging machine, an endless carrier supporting a series of trays adapted to feed blanks, means for feeding two separated charges onto each blank, means for moving a blank and its separated charges
50 into one of the receptacles or trays and thereby partially wrapping said blank around said charges while separated within the tray.

66. In a packaging machine, an endless carrier supporting a series of trays adapted to feed blanks, means for feeding two separated charges onto each blank, means for moving a blank and its separated charges into one of the receptacles or trays and thereby partially wrapping said blank around said separated charges, and means for folding a flap over each of said separated charges and pasting the same.

65 67. In a packaging machine, a support or table, an endless carrier supporting a series

of trays moving under said table and having a member projecting up above the table adapted to feed a blank along said table, means for charging or filling two separated charges on the blank, and means for moving the blank and its separated charges down through the table into one of the receptacles or trays. 70

68. In a packaging machine, an endless carrier supporting a series of trays adapted to feed blanks, means for feeding two separated charges onto each blank, means for moving a blank and its separated charges into one of the receptacles or trays and thereby partially wrapping said blank around said separated charges, means for ejecting the double package from said tray, and means for doubling the package on a line between the two charges so that one charge is in parallel relation to the other. 75 83 85

69. In a packaging machine, a support or table, an endless carrier supporting a series of trays moving under said table and having a member projecting up above the table adapted to feed a blank along said table, 90 means for charging or filling two separated charges on the blank, means for ejecting the double package from said tray, and means for doubling the package on a line between the two charges so that one charge is in parallel relation to the other. 95

70. In a packaging machine, a support or table, an endless carrier supporting a series of trays adapted to feed a blank along said support or table, means for charging or filling said blank with two separated charges, means for moving the separated charges and the blank into one of the trays, and folding the blank separately around said package, a pasting device for pasting the edges of the blank, and means for sealing the pasted parts of said blank separately around the two charges, thus forming a double package. 100 105

71. In a packaging machine, an endless carrier supporting a series of trays having openings through their bottoms, a support arranged to project upwardly through the trays when the trays come in alignment with said support, means for charging or filling a blank with separated charges while over the support, means for moving the blank and separated charges downward into the tray, thus partially folding the blank around said charge, a pasting device, and means for separately folding flaps over the two-part package within the tray. 110
115
120

125
72. In a packaging machine, a support or table having an opening or slot therein, a traveling receptacle or tray with an open bottom co-acting with said table and having a member projecting through said opening or slot to feed a blank along said table, charging or filling means adapted to fill separated charges on the blank, a support movable up through the bottom of the tray 130

to support the blank while receiving the separated charges, a plunger for moving said blank with its charge into the receptacle or tray and thereby folding the blank around the charges means for lowering the support as the charge enters the tray.

73. In a packaging machine, a support or table having an opening or slot therein, a traveling receptacle or tray with an open bottom co-acting with said table and having a member projecting through said opening or slot to feed a blank along said table, means for scoring the blank, charging or filling means adapted to fill separated charges on the blank, a support movable up through the bottom of the tray to support the blank while receiving the separated charges, a plunger for moving said blank with its charge into the receptacle or tray and thereby folding the blank around the charges means for lowering the support as the charge enters the tray.

74. In a packaging machine, a support or table having an opening or slot therein, a traveling receptacle or tray with an open bottom co-acting with said table and having a member projecting through said opening or slot to feed a blank along said table, charging or filling means adapted to fill separated charges on the blank, a support movable up through the bottom of the tray to support the blank while receiving the separated charges, means for pasting the edges of the blank, a plunger for moving said blank with its charges into the receptacle or tray and thereby folding the blank around the charges, the support lowering as the charge enters the tray, and means for sealing the pasted edges and thereby completing the package.

75. In a packaging machine, a support or table, an endless carrier supporting a series of trays adapted to feed the blank along said support or table, means for giving said carrier and its trays an intermittent motion, means for charging or filling said blank with two separated charges, a pasting device for pasting the edges of the blank, and means for folding the blank separately around said separated charges and for sealing the pasted parts.

76. In a packaging machine, a support or table, an endless carrier supporting a series of trays adapted to feed the blank along said support or table, means for giving said carrier and its trays an intermittent motion, means for charging or filling said blank with two separated charges, a pasting device for pasting the edges of the blank, means for folding the blank separately around said separated charges and for sealing the pasted parts, an ejector for ejecting the double package from said tray, and means for doubling the package on a line between the

two separated charges so that one charge is in parallel relation to the other.

77. In a packaging machine, means for supporting a blank, means for feeding two separated charges onto a blank, means for wrapping the blank separately around said separated charges, and a device having converging walls for doubling the package on a line between the two separated charges so that one charge is in parallel relation to the other.

78. In a packaging machine, a tray, means for feeding two separated charges onto a blank, means for moving said blank and its separated charges into said tray and thereby partially wrapping the blank around said separated charges, means for ejecting the double package from said tray, and a device having converging walls for doubling the package on a line between the two separated charges so that one charge is in parallel relation to the other.

79. In a packaging machine, an endless carrier supporting a series of trays, means for supporting a blank, means for feeding two separated charges onto a blank, means for moving the blank and its separated charges into one of the trays and thereby wrapping the blank around the separated charges, and a device having converging walls for doubling the package on a line between the two separated charges so that one charge is in parallel relation to the other.

80. In a packaging machine, an endless carrier supporting a series of trays, means for supporting a blank, means for feeding two separated charges onto a blank, means for moving the blank and its separated charges into one of the trays and thereby wrapping the blank around the separated charges, means for folding the edges over the separated charges, means for folding the flaps, and a device having converging walls for doubling the package on a line between the two separated charges so that one charge is in parallel relation to the other.

81. In a packaging machine, a support or table having an opening or slot therein, a traveling receptacle or tray with an open bottom co-acting with said table and having a member projecting through said opening or slot to feed a blank along said table, charging or filling means adapted to feed separated charges on the blank, a support movable up through the bottom of the tray to support the blank while receiving the separated charges, means for pasting the edges of the blank, a plunger for moving said blank with its charges into the receptacle or tray and thereby folding the blank around the charges, means for lowering the support as the charge enters the tray, means for sealing the pasted edges and thereby completing the package, an ejector for eject-

- ing the double package from said tray, and a device having converging walls for doubling the package on a line between the two separated charges so that one charge is in 5 parallel relation to the other.
82. In a packaging machine, means for supporting a blank, means for feeding two separated charges onto a blank, means for wrapping the blank around said separated 10 charges, a device having converging walls for doubling the package on a line between the two separated charges so that one charge is in parallel relation to the other, a delivery chute, and means for moving the 15 packages from the doubling device into said delivery chute.
83. In a packaging machine, means for supporting a blank, means for feeding two separated charges onto a blank, means for 20 wrapping the blank around said separated charges, a device having converging walls for doubling the package on a line between the two separated charges so that one charge is in parallel relation to the other, a delivery 25 chute, means for moving the packages from the doubling device into said delivery chute, and means for progressively moving the blanks through said delivery chute.
84. In a packaging machine, means for 30 supporting a blank, means for feeding two separated charges onto a blank, means for wrapping the blank around said separated charges, a device having converging walls for doubling the package on a line between 35 the two separated charges so that one charge is in parallel relation to the other, a delivery chute, and a pusher arranged to push the packages into said doubling device, whereby they are folded, and into the delivery 40 chute.
85. In a packaging machine, means for supporting a blank, means for feeding two separated charges onto a blank, means for wrapping the blank around said separated 45 charges, a device having converging walls for doubling the package on a line between the two separated charges so that one charge is in parallel relation to the other, a delivery chute, a pusher arranged to push the packages 50 into said doubling device, whereby they are folded, and into the delivery chute, and a second pusher to progressively push the packages through the delivery chute, making room for the next succeeding package.
86. In a packaging machine, a feeding device comprising a hopper, a roller or drum, and a chute or trough leading from said hopper and terminating in a frame-like receptacle of substantially the shape of the 55 package to be formed in combination with a tray for feeding a blank under said frame-like receptacle, and means for simultaneously forcing the blank and its charge into said tray, whereby the blank is partially wrapped around a charge as they both move 60 into said tray.
87. In a packaging machine, a feeding device comprising a hopper and a roller or drum, a chute or trough leading therefrom, and a receptacle or tray in which the package is partially formed, said chute or trough terminating in a frame-like receptacle of substantially the shape of said receptacle or tray said tray arranged to feed a blank under said frame-like receptacle in 65 combination with means for simultaneously forcing the blank and its charge into said tray, whereby the blank is partially wrapped around a charge as they both move into said tray.
88. In a packaging machine, a feeding device comprising a hopper, a roller or drum and a chute or trough leading therefrom, a table over which the blank is to be fed, said chute or trough supporting the charge 70 over said table as the blank is fed under the chute, and said chute or trough having a frame-like receptacle with an open bottom through which the charge is lowered onto the blank in combination with a tray 75 for feeding a blank under said frame-like receptacle, and means for simultaneously forcing the blank and its charge into said tray, whereby the blank is partially wrapped around a charge as they both move into said tray.
89. In a packaging machine, a feeding device comprising a hopper, a roller or drum and a chute or trough leading therefrom, a table over which the blank is to be fed, a 80 tray movable with respect to the table and under said chute and arranged to feed the blank over said table, the said chute supporting the charge over said table as the tray and blank are fed under the chute, and terminating in a frame-like receptacle with an open bottom, and a plunger for moving the charge 85 through said frame-like receptacle and simultaneously forcing the blank and charge into said tray and thereby partially wrapping the blank around said charge.
90. In a packaging machine, a feeding device comprising a hopper, a roller or drum and a chute or trough leading therefrom, a table over which the blank is to be fed, a 90 tray movable with respect to the table and under said chute and arranged to feed the blank over said table, the said chute supporting the charge over said table as the tray and blank are fed under the chute, and terminating in a frame-like receptacle with an open bottom, and a plunger for moving the charge 95 through said frame-like receptacle and simultaneously forcing the blank and charge into said tray and thereby partially wrapping the blank around said charge, means for folding the edges of the blank over the charge, a pasting device, for 100

1. In a packaging machine, a feeding device comprising a hopper, and a roller or drum therein arranged to feed or deliver two separated charges in combination with means for supporting and feeding a blank under said separated charges, and means for wrapping the blank separately around said charges. 70
2. In a packaging machine, a feeding device comprising a hopper, and a roller or drum therein arranged to feed or deliver two separated charges, combined with means for giving said roller drum intermittent motion and with means for supporting and feeding a blank under said separated charges, and means for wrapping the blank separately around said charges. 75
3. In a packaging machine, a feeding device comprising a hopper, and a roller or drum and a delivery chute arranged to feed or deliver two separated charges in combination with means for supporting and feeding a blank under said separated charges, and means for wrapping the blank separately around said charges. 80
4. In a packaging machine, a feeding device comprising a hopper, a roller or drum having its periphery arranged to feed separated charges in line with each other, and means for holding said charges separated as they are delivered from the hopper and roller in combination with means for supporting and feeding a blank under said separated charges, and means for wrapping the blank separately around said charges. 85
5. In a packaging machine, a feeding device comprising a hopper, a roller or drum having its periphery arranged to feed separated charges in line with each other, and a delivery chute having means for holding said charges separated as they are delivered in combination with means for supporting and feeding a blank under said separated charges, and means for wrapping the blank separately around said charges. 90
6. In a packaging machine, a feeding device comprising a hopper, a roller or drum having its periphery arranged to feed separated charges in line with each other, and a delivery chute having means for holding said charges separated as they are delivered, said chute having a frame-like terminal of substantially the same shape as the package to be made in combination with means for supporting and feeding a blank under said separated charges, and means for wrapping the blank separately around said charges. 105
7. In a packaging machine, a feeding device comprising a hopper, a roller or drum having its periphery arranged to feed separated charges in line with each other, a delivery chute having means for holding said charges separated as they are delivered, said chute having a frame-like terminal of substantially the same shape as the package to be made, a package forming mechanism, and means for moving the charge through said terminal into the package forming mech- 110
8. In a packaging machine, a tray and means for moving a charge and a blank into said tray whereby the sides of the blank project out of the tray over the charge, in combination with a folder having one portion acting upon one projecting side and another portion acting upon another side at an angle to the first named side, whereby one folder folds down two edges at an angle to each other. 115
9. In a packaging machine, a tray and means for moving a charge and a blank into said tray whereby the sides of the blank project out of the tray over the charge, in combination with a pair of folders each having one portion acting upon one projecting side and another portion acting upon another side at an angle to the first named side, said folders operating from opposite sides of the package. 120
10. In a packing machine, means for folding down the edges of the sides over the top of the package comprising a pair of folders each having one portion acting upon one projecting side and another portion acting upon another side at an angle to the first named side, said folders operating from opposite sides of the package, means for pasting a flap, and means for wrapping the flap over the edges wiped down by the folders and sealing the same. 125
11. In a packaging machine, a tray and means for moving a charge and a blank into said tray whereby the sides of the blank project out of the tray over the charge, in combination with a folder having one portion acting upon one projecting side and another portion acting upon another side at an angle to the first named side, whereby one folder folds down two edges at an angle to each other, means for pasting a flap, and means for wrapping the flap over the edges wiped down by the folders and sealing the same. 130
12. In a packaging machine, a tray and means for moving a charge and a blank into said tray whereby the sides of the blank project out of the tray over the charge, in combination with a pair of folders each having one portion acting upon one projecting side and another portion acting upon another side at an angle to the first named side, said folders operating from opposite sides of the package, means for pasting a flap, and means for wrapping the flap over the package and sealing the same. 135
13. In a packaging machine, a tray and means for moving a charge and a blank into said tray whereby the sides of the blank project out of the tray over the charge, in combination with a pair of folders each having one portion acting upon one projecting side and another portion acting upon another side at an angle to the first named side, said folders operating from opposite sides of the package, means for pasting a flap, and means for wrapping the flap over the package and sealing the same. 140

- project out of the tray over the charge, in combination with a folder having one portion acting upon one projecting side and another portion acting upon another side at an angle to the first named side, whereby one folder folds down two edges at an angle to each other, and a cam and intermediate parts for moving said folder over the top of the package to fold down said edges.

104. In a packaging machine, a tray and means for moving a charge and a blank into said tray whereby the sides of the blank project out of the tray over the charge, in combination with a pair of folders each having one portion acting upon one projecting side and another portion acting upon another side at an angle to the first named side, said folders operating from opposite sides of the package, in combination with cams and intermediate parts for moving said folders over the top of the package to fold down said edges.

105. In a packaging machine, a tray, a plunger for moving a blank and a charge into said tray whereby the edges of the blank project out of the tray, means for moving said plunger downward and then upward, and a folding plate acting in the same plane as the bottom of the plunger, having means for moving the plate over the package under the plunger to fold the edges of the blank after the plunger moves away from the top of the package.

106. In a packaging machine, a tray having an open bottom, a plunger for moving a blank and a charge into said tray whereby the edges of the blank project out of the tray, a support movable up through the open bottom of said tray, means for moving said plunger and support downward, and to then move the plunger upward, and a folder movable over the top of the package between the plunger and the package to fold the edges of the blank after the plunger moves away from the top of the package.

107. In a packaging machine, a tray having an open bottom, a plunger for moving a blank and a charge into said tray whereby the edges of the blank project out of the tray, a support movable up through the open bottom of said tray, means for moving said plunger and support downward, and to then move the plunger upward, a folder movable over the top of the package between the plunger and the package to fold the edges of the blank after the plunger moves away from the top of the package, means for pasting the blank, and means for folding and sealing the flap.

108. In a packaging machine, a tray having an open bottom, a plunger for moving a blank and a charge into said tray whereby the edges of the blank project out of the tray, a support movable up through the open bottom of said tray, means for moving said plunger and support downward, and to then move the plunger upward, a folder movable over the top of the package between the plunger and the package to fold the edges of the blank after the plunger moves away from the top of the package, means for pasting the blank, and means for folding and sealing the flap.

109. In a packaging machine, a pasting device comprising rotary pasters located at an angle to each other and arranged to apply paste to adjacent angularly disposed edges of a blank, one of said rotary pasters applying its paste slightly in advance of the other to avoid interference.

110. In a packaging machine, a pasting device comprising rotary pasters, each having a radially projecting pasting member, paste feeding rollers for feeding paste to said radially projecting members, one of said radial members being angularly disposed to the other whereby a corner may be pasted.

111. In a packaging machine, a pasting device comprising rotary pasters, each having a radially projecting pasting member, paste feeding rollers for feeding paste to said radially projecting members, one of said radially disposed members being angularly disposed to the other and acting slightly in advance of the other whereby a corner may be pasted without interference.

112. In a packaging machine, a pasting device comprising two sets of radial pasters located at an angle to each other and arranged to simultaneously apply paste to the corners of a blank, one pasting member of each set acting slightly in advance of the other whereby interference is avoided.

113. In a packaging machine, a blank supporting device, means for feeding two separated charges onto said blank, and said blank having two flaps to cover each of said separated charges, in combination with a pasting device comprising pasters arranged to apply paste to the angularly disposed edges of the flaps of said blank.

114. In a packaging machine, a table, an endless carrier supporting a series of trays having an intermittent motion and arranged to feed the blank along said table, a scoring device, a charging device and a pasting device all operating during the period of rest, a plunger to move the charge and the blank into a tray, folders folding over the edges of the sides of the blank, the edge of the table being formed to wipe the flap over the package and seal it as the tray during its period of movement travels with the package under the table, and an ejector for moving the package out of the tray.

115. In a packaging machine, a table, an endless carrier supporting a series of trays,

having an intermittent motion and arranged to feed the blank along said table, a scoring device, a charging device and a pasting device all operating during the period of rest, 5 a plunger to move the charge and the blank into a tray, folders folding over the edges of the sides of the blank, the edge of the table being formed to wipe the flap over the package and seal it as the tray during its 10 period of movement travels with the package under the table, an ejector for moving the package out of the tray, a pusher to move the package off of the ejector into a trough, and said trough having converging sides 15 whereby as the packages are forced thereinto they are doubled upon themselves.

116. In a packaging machine, a table, an endless carrier supporting a series of trays having an intermittent motion and arranged 20 to feed the blank along said table, a scoring device, a charging device and a pasting device all operating during the period of rest, a plunger to move the charge and the blank into a tray, folders folding over the edges 25 of the sides of the blank, the edge of the table being formed to wipe the flap over the package and seal it as the tray during its period of movement travels with the package under the table, an ejector for moving 30 the package out of the tray, a pusher to move the package off of the ejector into a trough, said trough having converging sides whereby as the packages are forced thereinto 35 they are doubled upon themselves, a delivery chute, and a pusher for moving the packages forward in the chute to make room for the next succeeding package.

117. In a packaging machine, a table, having two openings and a longitudinal slot, an 40 endless carrier supporting a series of trays movable with respect to the table and having members projecting upward above the face of the table to move a blank along the table, a charging device for placing a charge 45 on a blank carried by one of the trays, means for moving the blank and its charge through one of said openings into the tray and thus partially forming the package, the tray containing the package moving under the table, 50 and an ejector for moving the completed package out of the tray up through the other opening in the table.

118. In a packaging machine, a table having two openings and a longitudinal slot, an 55 endless carrier supporting a series of trays movable with respect to the table and having members projecting upward above the face of the table to move a blank along the table, a charging device for placing a charge on a 60 blank carried by one of the trays, means for moving the blank and its charge through one of said openings into the tray and thus partially forming the package, the tray containing the package moving under the table 65 and thereby wiping a flap over the package,

and an ejector for moving the completed package out of the tray up through the other opening in the table.

119. In a packaging machine, a table having two openings and a longitudinal slot, 70 an endless carrier supporting a series of trays movable with respect to the table and having members projecting upward above the face of the table to move a blank along the table, a charging device for placing a 75 charge on a blank carried by one of the trays, means for moving the blank and its charge through one of said openings into the tray and thus partially forming the package, means for pasting the flap, the tray containing the package moving under the table and thereby wiping a flap over the package, and an ejector for moving the completed package out of the tray up through the other opening 80 in the table.

120. In a packaging machine, a table, an endless carrier supporting a series of trays, a cam and ratchet wheel for giving said carrier and tray an intermittent motion to feed the blank along said table; a scoring device 90 and a cam for operating the same, a charging device, and a cam for operating the same, and a pasting device all operating during the period of rest, a plunger to move the charge and the blank into a tray; folders 95 folding over the edges of the sides of the blank and cams for operating the same; the edge of the table being formed to wipe the flap over the package and seal it as the tray during its period of movement travels with the package under the table; an ejector for moving the package out of the tray and a cam for operating the same; and a pusher to move the package off of the ejector into a trough and a cam for operating the same; 100 said trough having converging sides whereby as the packages are forced thereinto they are doubled upon themselves.

121. In a packaging machine, a table, an endless carrier supporting a series of trays, a cam and ratchet wheel for giving said carrier and trays an intermittent motion to feed the blank along said table; a scoring device and a cam for operating the same, a 110 charging device, and a cam for operating the same; and a pasting device all operating during the period of rest, a plunger to move the charge and the blank into a tray operated from the cam which operates the scoring device; folders folding over the edges of the sides of the blank and cams for operating the same; the edge of the table being formed to wipe the flap over the package and seal it as the tray during its period of movement travels with the package under the table; an ejector for moving the package out of the tray and a cam for operating the same; and a pusher to move the package off of the ejector into a trough and a cam for 115 operating the same; said trough having converging sides whereby as the packages are forced thereinto they are doubled upon themselves.

122. In a packaging machine, a table, an endless carrier supporting a series of trays, a cam and ratchet wheel for giving said carrier and trays an intermittent motion to feed the blank along said table; a scoring device and a cam for operating the same, a 120 charging device, and a cam for operating the same; and a pasting device all operating during the period of rest, a plunger to move the charge and the blank into a tray operated from the cam which operates the scoring device; folders folding over the edges of the sides of the blank and cams for operating the same; the edge of the table being formed to wipe the flap over the package and seal it as the tray during its period of movement travels with the package under the table; an ejector for moving the package out of the tray and a cam for operating the same; and a pusher to move the package off of the ejector into a trough and a cam for 125 operating the same; said trough having converging sides whereby as the packages are forced thereinto they are doubled upon themselves.

123. In a packaging machine, a table, an endless carrier supporting a series of trays, a cam and ratchet wheel for giving said carrier and trays an intermittent motion to feed the blank along said table; a scoring device and a cam for operating the same, a 130 charging device, and a cam for operating the same; and a pasting device all operating during the period of rest, a plunger to move the charge and the blank into a tray operated from the cam which operates the scoring device; folders folding over the edges of the sides of the blank and cams for operating the same; the edge of the table being formed to wipe the flap over the package and seal it as the tray during its period of movement travels with the package under the table; an ejector for moving the package out of the tray and a cam for operating the same; and a pusher to move the package off of the ejector into a trough and a cam for operating the same; said trough having converging sides whereby as the packages are forced thereinto they are doubled upon themselves.

... and sides whereby as the packages are passed therefrom they are doubled upon themselves.

123. In a packaging machine, a table or support, an endless carrier supporting a series of trays movable with respect to the table and having members projecting upward above the face of the table to move a double blank along the table, a charging device for feeding two separated charges onto the blank, means for moving the blank and its separated charges through the table into one of said trays, folding and pasting means, a device having converging walls for doubling the package so that one charge is in parallel relation to the other, and means for moving the package from the trays into said device with the converging walls.

124. In a packaging machine, a table or support, an endless carrier supporting a series of trays movable with respect to the table and having members projecting upward above the face of the table to move a double blank along the table, a charging device for feeding two separated charges onto the blank, means for moving the blank and its separated charges through the table into one of said trays, folding and pasting means,

a device having converging walls for doubling the package on a line between the two separated charges so that one charge is in parallel relation to the other, means for moving the package from the trays into said device with the converging walls, a delivery chute, and a pusher to progressively push the packages through the delivery chute making room for the next succeeding package.

124. In a packaging machine, a feeding device comprising a hopper, a roller or drum and a chute or trough leading therefrom, a table over which the blank is to be fed, a tray for feeding a blank over said table and under said chute, said chute supporting the charge over the table as the blank is fed under it, and means for simultaneously forcing the blank and its charge into said tray, thereby partially wrapping the blank around said charge as they both enter the tray.

Signed by me at Lynchburg, Va. this 17th day of February 1909.

MICHAEL KIRSHNER.
